UNITED STATES PATENT OFFICE.

ADOLPH MÜNKER, OF SCHOENEBERG, GERMANY.

ELECTROTHERMOSTATIC CABLE FOR FIRE-ALARMS.

SPECIFICATION forming part of Letters Patent No. 664,966, dated January 1, 1901.

Application filed April 14, 1900. Serial No. 12,856. (No model.)

To all whom it may concern:

Be it known that I, ADOLPH MÜNKER, lithographer, a subject of the Emperor of Germany, residing at 40 Grunewaldstrasse, 5 Schoeneberg, near Berlin, in the Kingdom of Prussia, German Empire, have invented a new and useful Electrothermostatic Cable for Fire-Alarms, of which the following is a full, clear, and exact specification.

10 My invention consists of a new and useful electrothermostatic cable for fire-alarms; and its object is to provide a wire conductor of the cable form in which two conducting-wires insulated from each other and normally out 15 of electrical contact are adapted to complete an electric circuit containing the fire-alarm apparatus by the fusion of a melting piece inserted between two elastic contacts, which are secured to the conducting-wires by soldering or in any similar manner before insulating 20 the wires from each other, so that the ends of said contacts after insulating and winding project out of the insulating-envelop. The cable has the thus-formed thermal circuit-closers secured to it at any suitable distance 25 from each other, for the purpose required. This cable thus provided with numerous circuit-closers of the described form will cause an alarm to be operated at every dangerous 30 increase of temperature in the rooms in which such a cable is placed.

The accompanying sheet of drawings shows in Figure 1, a short length of the cable, its insulating-envelop being broken away at 35 its ends to show the two conducting-wires. Fig. 2 is a cross-sectional view of the cable, showing one of the thermal circuit-closers forming part thereof. Fig. 3 shows a plan view of the cable, the insulating-covering and

the circuit-closer being partly shown in section. Fig. 4 illustrates a diagram of the cable to be connected to a fire-alarm apparatus not shown.

Before insulating the two conducting-wires *a* and *b* the two elastic contacts *c* are respectively secured to the wires by soldering or in any similar manner, as shown in Fig. 2, so that said contacts *c* after insulating and winding partially project out of the insulating-envelop *e*. Between said elastic contacts 45 *c* are clamped thin insulating-pieces *d*, of a fusible material melting easily and without residuum at any dangerous increase of temperature—such as paraffin, stearin, and the like. This cable, connected at one end to the 50 circuit of a single fire-alarm bell, will give a signal for every increase of heat at all points of the cable provided with the thermal circuit-closers, because the circuit is instantly closed if one of the fusible pieces melts by an 55 increase of heat.

What I claim as my invention is—

An electrothermostatic cable for fire-alarms consisting of two conducting-wires insulated from each other and a suitable number of 60 thermal circuit-closers forming part of the cable, said circuit-closers consisting of two elastic contacts respectively secured to the conducting-wires before insulating and a fusible piece between said contacts, substantially as described.

In witness whereof I have hereunto signed my name, this 16th day of March, 1900, in the presence of two subscribing witnesses.

ADOLPH MÜNKER.
